FACE SUPPORT FOR BINOCULARS

Aaron H. Hoffeditz, Greencastle, Pa.

Application July 1, 1941, Serial No. 400,644

13 Claims. (Cl. 88—34)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to a face support for binoculars and more particularly to a support of this type having a face piece which conforms exactly to the lineaments of the user's face around the forehead, eyes and nose.

In all of the existing face supports for binoculars with which I am familiar, pads or cushions have been provided in an effort to make the support more comfortable on the face of the user. Despite the use of these cushions, however, the pressure areas which are created where the cushions bear against the face are likely to stop the circulation of the blood in these spots and so result in considerable discomfort to the user when the binoculars are maintained on the face for long periods of time. It is, therefore, the object of my invention to provide a binocular support having a face piece which bears against a large area of the face around the forehead, eyes and nose, and which is molded to accurately conform to the contours of these parts of the face. Consequently, no localized pressure areas are created, the face piece bearing with equal intensity on all parts of the face covered by it. As a result it is possible to wear my support for as long a time as is necessary or desirable without any discomfort to the user. My support is particularly adapted for use by airplane or balloon observers who must maintain the binoculars up to the eyes for considerable lengths of time and who have also to contend with watering of the eyes as a result of the high winds encountered. With my device all wind is prevented from reaching the eyes of the wearer and hence, there is no possibility of the eyes watering from this cause. It is to be understood, however, that this is not the only possible use of my invention but that it will also find a large field of use by artillery observers, naval observers and even by sports enthusiasts where the sporting event is one of long duration, such as a foot-ball game, a base-ball game, a boat race, etc.

Another object of my invention is to provide a binocular supporting device which may be used with binoculars of conventional design and which will permit all of the usual adjustments of the binoculars to be made, such as changing the interpupillary distance between the eyepieces, focusing the eyepieces in unison and adjusting the individual eyepieces separately.

A further object of my invention is to provide a means for holding the binocular support securely to the head of the wearer so as to make it possible to support even a heavy pair of binoculars from the head without using any great degree of tension in the head strap or any supplementary air from the hands. This is accomplished by attaching the head strap to the forward end of the device instead of to the sides of the face piece as has been the custom heretofore, and also by attaching it at a point lying above the center of gravity of the device as a whole. This results in the support and the binoculars being hung from the head rather than being held thereto by an excessive pressure acting in a direction normal to the face of the wearer.

With these and other objects in view, the invention consists of certain novel features of construction and arrangement as will be more fully described and pointed out in the appended claims.

In the drawings:

Figure 1 is a perspective view of my device showing a conventional pair of binoculars supported therein.

Figure 2 is an exploded perspective view of my device with the binoculars removed to show in detail the shape and arrangement of the various parts constituting the same.

As shown in Figures 1 and 2, my binocular support is comprised of a face piece 1, having a face conforming surface 2 which is made to accurately conform to the features of the individual who is to use the same, around the forehead, eyes and nose. Any one of several different methods may be used to accomplish this, one of these methods being to make a plaster cast of this area of the individual's face and then casting the piece 1 out of aluminum, or any other suitable material. An alternative method would be to make several standard face pieces which conform roughly to the outlines of several standard types of faces, and then coating the surface 2 of the piece with a thermal hardening or air hardening plastic of suitable characteristics. This plastic surface may then be pressed against the individual's face to take the shape thereof and then removed and laid aside to set. A third possible method would be to make a cast of the face and then mold a rubber lining for one of the standard face pieces mentioned in the alternative method set out above in the exact shape of this plaster cast, which lining may then be bonded to the standard face piece.

The face piece 1 is provided with a pair of open-

ings 3 to accommodate the eyepieces of the binoculars. The piece is notched, as at 4 to accommodate the bridge of the nose and a flange 5 is formed on the surface 2 so as to provide a larger bearing area of the piece against the face. A binocular mounting plate 6 is provided when certain standard face pieces, as mentioned above, are to be used. If a separate face piece is to be cast for each individual, then it may be found desirable to eliminate the plate 6 and mount the binocular supporting structure directly on the face piece. However this may be, the plate 6 is provided with a pair of elongated holes 7 to receive the eyepieces of the binoculars. The holes are elongated in order that the interpupillary distances between the eyepieces may be adjusted to suit the individual wearing the same, the holes 3 in piece 1 being so spaced apart as to conform to the distance between the eyes of the individual who is to use the same. If standard pieces 1 are to be used as mentioned in the preceding paragraph, the holes 3 would not, of course be bored out until the piece is fitted to the face of the individual when they would be spaced in accordance with his particular eye measurements. This plate 6 is standard for all face supports and is fastened to the individual face pieces 1 by means of the screws 8 extending through the elongated slots 9 and threading into the tapped holes 10 in piece 1. The plate 6 may be adjusted up or down on piece 1 by means of the elongated holes 9, this being necessary in order to take care of any adjustments which are made in the distance between the eyepieces. If desired, a rubber gasket cut to the shape of plate 6 and having round holes cut therein to conform to the distance between the eyes of the user may be inserted between plates 6 and piece 1 to remove all possibility of any wind reaching the eyes around the eyepieces. The holes cut in the rubber gasket should be of such size as to fit snugly around the eyepieces of the binoculars, thus tightly sealing the eye openings and preventing the entry of any outside wind.

Secured in the plate 6 are three rods 11, upon which is slidably mounted a triangularly shaped binocular supporting block 12. This block is provided with three holes 13, which are spaced in accordance with the spacing of rods 11. The block 12 is split in half as shown at 14, and is bored lengthwise with a hole 15 of a diameter slightly smaller than that of the hinge shaft of the binoculars to be supported in the device. Four screws 16 are located in holes 17 bored through the top half of the block, these screws being received in tapped holes provided in the lower half of the block.

By means of this arrangement the halves of the block 12 may be placed on opposite sides of the hinge shaft of the binoculars and may then be securely clamped thereto by means of the screws 16. The block slides on the rods 11 and is prevented from slipping off the ends of the rods by a triangularly shaped end plate 18 having holes 18' fitting over the tapped ends of the rods 11. The plate is held in place by the nuts 19 screwing on the ends of rods 11. The eyepiece assembly of the binoculars may be adjusted in or out relative to the piece 1 and the plate 6 in order that the eyecups thereof may be brought into proper position with respect to the eye sockets of the wearer. This is accomplished by the use of various sized spacing collars secured to the forward end of the hinge shaft of the binoculars. After a collar 20 of suitable length has

been selected, it may be fastened securely to the shaft by means of a set screw 21. The eyepiece assembly is held in this adjusted position by means of a triangularly shaped clamping plate 22. This plate is bored with three holes 23 of such diameter and in such location as to slide over the rods 11. A semicircular recess 23' having a diameter somewhat greater than that of the focusing screw of the binoculars is provided in the plate to allow for clearance of this screw when the plate is in position. Four tapped holes 24 are provided in the plate in the locations shown, these holes receiving the threaded ends of four long screws 25 extending through holes in the plate 6. Sleeves 26 are slid on the screws 25 and thus serve to space the plate 22 a distance from plate 6 equal to the length of these sleeves. The eyepiece adjusting bar 27 of the binoculars (Fig. 1) lies in the space thus provided between these two plates. The sleeves 26 are of such length (consideration being given to the length of collar 20) that the bar 27 will be held snugly in position between the plates 6 and 22 with little or no end play. Thus it will be seen that the extent to which the eyepieces of the binoculars protrude within the holes 3 in the face piece 1 depends upon the width of the collar 20 and, that once this dimension is fixed and the proper length of sleeves 26 is chosen, the eyepiece assembly of the binoculars will be held in fixed position with respect to the face piece. During movement of the focusing screw 28 of the binoculars, the body portion of the binoculars and the block 12 will be slid along the rods 11 while the eyepieces remain stationary. It will thus be seen that the binoculars are securely mounted on the face piece and that no motion of the binoculars relative thereto will occur except during focusing operations when the body portion of the instrument will slide along the supporting rods.

The binocular support is held in place against the face of the user by means of a headband 29 which is attached, by means of a snapfastener 30, to an upper extension 31 of the end plate 18. The band passes around the back of the head and may be made from any suitable elastic material, provision being made, of course, for adjustment in the length of the band. It will be noted that the band is attached to the forward end of the binocular support and, also, that the point of attachment is located above the center of gravity of the device, binoculars included. This makes it possible to support the structure without undue tension in the headband 29 and without requiring additional support by the hands of the user. This, of course, is due to the fact that the attachment of the headband at this point tends to hang the device from the head rather than attempting to support it by pulling it directly against the face. The attachment of the band at this point has the further advantage that in removing the binoculars from the head, it is only necessary to pull them slightly forward away from the face and then, by swinging the face piece down away from the eyes, the strap 29 will be loosened and may be readily removed from around the back of the head.

Fig. 1 shows the manner in which a pair of binoculars 32 of conventional design are supported in my device. As mentioned earlier in this description, 27 represents the focusing bar of the instrument while 28 represents the focusing screw thereof. The eyepieces are designated

as 33 and 34 while the hinge straps are numbered 35 and 36.

It will now be evident that I have provided a face support for binoculars which is simple in construction but perfectly suited for the purpose intended. The parts going into the structure are preferably made of aluminum or of alloys thereof so as to render the device as light as possible on the head of the wearer. It is also to be noted that specially designed binoculars to fit the face support are not necessary, but that any binocular of conventional design may be supported therein.

Having thus described my invention, what I claim as new and desire to secure by Letters Patent is:

1. In a device of the character described comprising a rigid face piece shaped to accurately conform to the lineaments of a particular individual's face around the forehead, eyes, and nose and having openings therein for receiving the eyepieces of a pair of conventional binoculars, a plurality of parallel supporting rods secured to said face piece, a supporting member securely fastened to the body portion of the binoculars and slidably mounted on said rods, and means for holding the eyepiece assembly of the binoculars in fixed relationship to said face piece.

2. In a device of the character described comprising a rigid face piece shaped to accurately conform to the lineaments of a particular individual's face around the forehead, eyes and nose and having openings therein for receiving the eyepieces of a pair of conventional binoculars, a plurality of parallel supporting rods secured to said face piece, a supporting member securely fastened to the body portion of the binoculars and adapted for sliding movement along said rods, and means engaging the eyepiece focusing bar of the binoculars for rigidly securing the binocular eyepiece assembly to said face piece.

3. In a device of the character described comprising a face piece having openings therein for receiving the eyepieces of a pair of binoculars, a plurality of parallel supporting rods secured to said face piece, a supporting member securely fastened to the body portion of the binoculars and adapted for sliding movement along said rods, and an eyepiece assembly retaining plate fixed in spaced relationship to said mounting plate in order that the eyepiece focusing bar of the binoculars may be embraced between the two plates to thereby hold the binocular eyepiece assembly in fixed relationship to said face piece.

4. In a device of the character described comprising a face piece having openings therein for receiving the eyepieces of a pair of binoculars, a plurality of parallel supporting rods secured to said face piece, a supporting member securely fastened to the body portion of the binoculars and adapted for sliding movement along said rods, a spacing collar fitting over the end of the binocular hinge shaft adjacent to the binocular focusing screw for determining the position of the eye pieces with respect to said face piece, and an eyepiece assembly retaining plate fixed in spaced relationship to said mounting plate in order that the eyepiece focusing bar of the binoculars may be embraced between the two plates to thereby hold the binocular eyepiece assembly in fixed relationship to said face piece.

5. In a device of the character described comprising a face piece shaped to accurately conform to the lineaments of a particular individual's face around the forehead, eyes and nose and

having openings therein for receiving the eyepieces of a pair of binoculars; a binocular supporting structure mounted on said face piece, said structure including a plate having openings therein for receiving the binocular eyepieces, a plurality of parallel rods secured to said plate, and a supporting member securely fastened to the body portion of the binoculars and slidably mounted on said rods; and means for holding the eyepiece assembly of the binoculars in fixed relationship to said face piece.

6. In a device of the character described comprising a face piece shaped to accurately conform to the lineaments of a particular individual's face around the forehead, eyes and nose and having circular openings therein for receiving the eyepieces of a pair of binoculars; a binocular supporting structure slidably mounted for vertical adjustment on said face piece, said structure including a plate having elongated holes therein for receiving the binocular eyepieces, a plurality of parallel rods secured to said plate, and a supporting member securely fastened to the body portion of the binoculars and slidably mounted on said rods; and means for holding the eyepiece assembly of the binoculars in fixed relationship to said face piece.

7. In a device of the character described comprising a face piece shaped to accurately conform to the lineaments of a particular individual's face around the forehead, eyes and nose and having circular openings therein for receiving the eyepieces of a pair of binoculars; a binocular supporting structure slidably mounted for vertical adjustment on said face piece, said structure including a plate having elongated holes therein for receiving the binocular eyepieces, a plurality of parallel rods secured to said plate, and a supporting member securely fastened to the body portion of the binoculars and slidably mounted on said rods; and means for holding the eyepiece assembly of the binoculars in fixed relationship to said face piece.

8. In a device of the character described comprising a face piece shaped to accurately conform to the lineaments of a particular individual's face around the forehead, eyes and nose and having circular openings therein for receiving the eyepieces of a pair of binoculars; a binocular supporting structure slidably mounted for vertical adjustment on said face piece, said structure including a plate having elongated holes therein for receiving the binocular eyepieces, a plurality of parallel rods secured to said plate, and a supporting member securely fastened to the body portion of the binoculars and slidably mounted on said rods; and an eyepiece assembly retaining plate fixed in spaced relationship to said mounting plate in order that the eyepiece focusing bar of the binoculars may be embraced between the two plates to thereby hold the binocular eyepiece assembly in fixed relationship to said face piece.

9. In a device of the character described comprising a face piece shaped to accurately conform to the lineaments of a particular user's face around the forehead, eyes and nose and having circular openings therein for receiving the eyepieces of a pair of binoculars; a binocular supporting structure slidably mounted for vertical adjustment on said face piece, said structure including a mounting plate having elongated holes therein for receiving the binocular eyepieces, a plurality of parallel rods secured to said plate, and a supporting member securely fastened to

the body portion of the binoculars and slidably mounted on said rods; a spacing collar fitting over the end of the binocular hinge shaft adjacent to the binocular focusing screw for determining the position of the eyepieces with respect to said face piece; and an eyepiece assembly retaining plate fixed in spaced relationship to said mounting plate in order that the focusing bar for the binocular eyepieces may be embraced between the two plates to thereby hold the binocular eyepiece assembly in fixed relationship to said face piece.

10. A face support for an optical instrument comprised of a rigid face piece shaped to exactly conform to the lineaments of a particular individual's face over a considerable area around the forehead, eyes and nose.

11. A face support for an optical instrument comprising a rigid face piece having a face conforming portion shaped to accurately contact a considerable area of a particular individual's

face around the forehead, eyes and nose, and an instrument mounting portion for receiving an instrument supporting structure.

12. A face support for an optical instrument comprised of a rigid face piece shaped to exactly conform to the lineaments of a particular individual's face over a considerable area around the forehead, eyes and nose, said face piece having openings therein for receiving the eyepieces of the instrument.

13. In a device of the character described comprising a rigid face piece shaped to exactly conform to the lineaments of a particular individual's face over a considerable area around the forehead, eyes, and nose and having openings therein for receiving the eyepieces of a pair of conventional binoculars, and means for rigidly securing said binoculars to said face piece so as to prevent relative movement between the binoculars and said face piece.

AARON H. HOFFEDITZ.
